Letters Patent No. 181981, Dated Aug. 22, 1864.

Design for the Plates of a Cooking Stove.

The subject is referred to in these Letters Patent and making part of the same.

Isaac De Fouché,
To all whom it may concern:

Be it known that I, Isaac De Fouché, of the City of St. Louis, in the County of St. Louis, and State of Missouri, have invented or produced a new and original Design for the Plates of a cooking stove; and I do hereby declare that the following is a full and exact description of the same, reference being had to the accompanying photographed drawings and to the letters of reference marked thereon, making a part of this Specification in which Fig. 1 represents the oven doors, decorated with the band and bead ornaments A and B, the figure C, being incorporated with the larger ornament at D, as shown. Fig. 2, represents the fire door, decorated with the band and bead ornament E, as shown. Fig. 3 represents the front doors, one door being the exact counterpart of the other, decorated with the band and bead ornaments F, as shown.

Having thus described my design for the plates of a cooking stove, what I claim as new therein, and desire to secure by letters Patent, is—

The ornamental configuration and design for the plates of a cooking stove, as herein described and shown in the accompanying drawings.

Witnessed,

John Woodroof,

John W. Allen

Isaac De Fouché.
